ATTORNEYS

UNITED STATES PATENT OFFICE.

JOSEPH O. McGEE, OF WESTPOINT, TENNESSEE.

DESIGN FOR A HOE.

53,637.

Specification for Design.

Patented July 22, 1919.

Application filed December 6, 1917. Serial No. 205,901. Term of patent 14 years.

To all whom it may concern:

Be it known that I, JOSEPH O. McGEE, a citizen of the United States, residing at Westpoint, in the county of Lawrence and State of Tennessee, have invented a new, original, and ornamental Design for Hoes, of which the following is a specification, reference being had to the accompanying drawing, forming a part thereof.

In the drawing,

Fig. 2 is a side elevation thereof, and
Fig. 3 is a plan view.

I claim:

The ornamental design for a hoe as shown.
In testimony whereof I affix my signature.

JOSEPH O. McGEE.
